UNITED STATES PATENT OFFICE

134,199

DESIGN FOR A COMBINATION BATHROOM UNIT

David E. Anderson, Los Angeles, Calif.

Application February 18, 1942, Serial No. 105,860

Term of patent 14 years

To all whom it may concern:

Be it known that I, David E. Anderson, a citizen of the United States, residing at Los Angeles, in the county of Los Angeles and State of California, have invented a new, original, and ornamental Design for a Combination Bathroom Unit, of which the following is a specification, reference being had to the accompanying drawings, forming part thereof.

Fig. 1 is a perspective view of a combination bathroom unit of my new design.

Fig. 2 is a top plan view of the combination bathroom unit shown in Fig. 1.

I claim:

The ornamental design for a combination bathroom unit, as shown.

DAVID E. ANDERSON.
